poration of Ohio

Application May 3, 1946, Serial No. 129,267

Term of patent 14 years

(Cl. D48—4)

To all whom it may concern:

Be it known that we, Charles Forest Bookman, Jr., and Zia H. Jammé, citizens of the United States, residing at University Heights and Cleveland, in the county of Cuyahoga and State of Ohio, have jointly invented a new, original, and ornamental Design for Combined Bracket Lamp Socket and Control Switch, of which the following is a specification, reference being had to the accompanying drawings, forming a part thereof.

In the drawings, in which the dominant features of our design reside in the portions shown in full lines:

Figure 1 is a front elevation of a combined bracket lamp socket and control switch, showing our new design;

Figure 2 is a side elevation of the socket shown in Figure 1; and

Figure 3 is a bottom plan view, looking upwardly, of the article shown in Figures 1 and 2.

We claim:

The ornamental design for a combined bracket lamp socket and control switch, substantially as shown and described.

CHARLES FOREST BOOKMAN, JR.

ZIA H. JAMMÉ.
